CHARLES FORSTER, OF LEBANON, PENNSYLVANIA.

Letters Patent No. 71,376, dated November 26, 1867.

IMPROVEMENT IN PLOUGHS.

The Schedule referred to in these Letters Patent and making part of the same.

TO ALL WHOM IT MAY CONCERN:

Be it known that I, CHARLES FORSTER, of Lebanon, in the county of Lebanon, and State of Pennsylvania, have invented a new and useful Improvement in Ploughs; and I do hereby declare that the following is a full, clear, and exact description thereof, which will enable others skilled in the art to make and use the same, reference being had to the accompanying drawings, forming part of this specification.

Figure 1 is a side view of my improved plough.

Figure 2 is the same view as fig. 1, the shear-cutter and land-side being removed.

Figure 3 is a detail view of the land-side detached from the plough.

Figure 4 is a detail view of the inner side of the cutter.

Figure 5 is a detail top view of the shear.

Similar letters of reference indicate corresponding parts.

My invention has for its object to improve the manner in which the cutter and land-side are connected to each other and to the standard and mould-board, so as to make the connection stronger, firmer, and more secure; and it consists in forming grooves or recesses in the standard or forward end of the mould-board to receive the flange and tongue formed upon the forward end of the land-side, and in forming a recess or groove in the side of the flange upon the forward end of the land-side to receive a projection formed upon the inner side of the rear part of the cutter; the whole being constructed and arranged as hereinafter more fully described.

A are the handles, B is the beam, C is the standard, and D is the mould-board of the plough. The standard C and mould-board D may, if desired, be cast in one piece, as shown in fig. 2. Upon the side of the standard C is formed a recess or shoulder to receive the flange e^1 of the land-side E. At the point where the upper bolt passes through, the recess c^1 of the standard C is extended, as shown at the point c^2 in fig. 2, to receive the tongue e^2 formed upon the flange e^1 , through which the said bolt passes. Upon the side of the flange e^1 is formed a recess or groove, e^3 , to receive a projection, f' , formed upon the inner side of the rear part of the cutter F to make the connection between the cutter and land-side stronger. Upon the inner side of the flange e^1 of the land-side E, exactly opposite the recess e^3 , is formed a projection to strengthen the flange e^1 that would otherwise be weakened by the formation of the recess e^3 , making that part as strong, or stronger than any other part of the said flange. F is the cutter, which is fitted to the standard C and to the land-side E, so that the outer surface of the said cutter and land-side may be in the same plane. The cutter, land-side, and mould-board are secured together by bolts, the upper bolt passing through the mould-board D, tongue e^2 of the flange e^1 of the land-side E, and through the cutter F. The forward lower bolt passes through the mould-board and cutter, and the rear, lower bolt through the land-side and cutter, as shown in figs. 1 and 2. G is the shear, which is bolted to the mould-board D and to the handles A in the usual manner, being also secured to the beam B by the long bolt H. By this construction the cutter, land-side, and mould-board are firmly and strongly secured together so as to be able to resist any strain that may be brought upon them, and so as to be easily detached and removed, when desired.

I claim as new, and desire to secure by Letters Patent—

1. Forming recesses c^1 c^2 in the standard C or forward end of the mould-board D to receive the flange e^1 and tongue e^2 formed upon the forward end of the land-side E, substantially as herein shown and described and for the purpose set forth.
2. Forming a recess or groove, e^3 , in the outer side of the flange e^1 of the land-side E for the reception of the projection f' formed upon the inner side of the rear part of the cutter F, substantially as herein shown and described and for the purpose set forth.

CHARLES FORSTER.
